UNITED STATES PATENT OFFICE

121,880

DESIGN FOR A CABINET FOR AN AIR CONDITIONING UNIT OR SIMILAR ARTICLE

Samuel J. Levine, East Orange, N. J., assignor to General Electric Company, a corporation of New York

Application February 28, 1940, Serial No. 90,579

Term of patent 14 years

To all whom it may concern:

Be it known that I, Samuel J. Levine, a citizen of the United States, residing at East Orange, in the county of Essex, State of New Jersey, have invented a new, original, and ornamental Design for a Cabinet for an Air Conditioning Unit or Similar Article, of which the following is a specification, reference being had to the accompanying drawing, forming a part thereof.

The single figure of the drawing is a perspective view of a cabinet for an air conditioning unit or

similar article embodying my new design. The left end of the cabinet as viewed in the drawing is like the right end shown in the drawing, the cabinet being laterally symmetrical as viewed from the front.

I claim:

The ornamental design for a cabinet for an air conditioning unit or similar article, substantially as shown and described.

SAMUEL J. LEVINE.
